1

This invention relates to the production of oxygen by the liquefaction and rectification of air.

All temperatures herein are in degrees F. and pressures in pounds per square inch gauge.

Oxygen is commonly produced by liquefaction of air and rectification at low temperatures. The refrigeration necessary for liquefaction is supplied to the air after it has been compressed and water-cooled to approximately room temperature by indirect heat exchange with the effluent products of rectification. One of the more recent methods of producing oxygen involves flowing the incoming air through a reversing exchanger through which flows a rectification product such as nitrogen or oxygen, the air recovering the cold content of the rectification product and being thus cooled to a temperature close to its liquefaction point at the pressure existing in the heat exchange zone, thereby substantially completely removing all carbon dioxide present in the air. A minor portion of the thus cooled air stream is thereafter warmed by heat exchange with one of the warmer streams of fluid media flowing in the system, preferably by passage through the aforesaid heat exchange zone, to a temperature such that upon subsequent expansion little or no condensation or formation of liquid air in the expander takes place. The thus warmed minor portion is expanded to produce the refrigeration necessary to compensate for cold losses resulting from the difference in enthalpy between the incoming air and the outgoing products of rectification and for heat leaks into the system, and the expanded air is introduced into the rectification system where it is rectified to recover the oxygen content thereof. The remaining major portion of the air is also introduced into the rectification system where it is rectified. The flow of air and that of the rectification product are periodically reversed in the reversing heat exchanger, so that upon each of the reversals the rectification product substantially completely removes the carbon dioxide and other condensibles deposited in the reversing exchanger during the preceding step of the process. Such reversal may take place about every three minutes. It has also been proposed to recycle through at least the cold end of the reversing exchanger nitrogen, oxygen, or an extraneous gas to facilitate purging of the exchanger.

In operation, it has been found that the temperatures of the gaseous streams leaving reversing exchangers fluctuate within wide limits, sometimes as much as 10° F., or more. Such

2

fluctuations cause considerable disturbance in the operation of the oxygen plant and impair its efficiency. For instance, fluctuations in the temperature of the air flowing to the expander interferes with its best performance. Likewise, these temperature variations may lead to the formation of liquid air within the reversing exchangers during certain portions of the reversal cycles with consequent loss of air during the subsequent cycles when a rectification product stream is used to purge the reversing exchangers of constituents deposited therein by the air. These temperature variations also deleteriously affect the operation of the rectification system.

The causes of temperature fluctuations in the gaseous streams leaving reversing exchangers are manifold. In recuperative-type reversing exchangers, the principal cause of temperature fluctuations is the asymmetrical arrangement of the flow paths in the exchanger; typically, a recuperative reversing exchanger will have three flow paths formed by three concentric pipes of increasing diameter, the smallest central pipe being used for a recycle stream, the annulus between the smallest and intermediate pipes and the annulus between the intermediate and largest pipes being alternately used for the flow of air and a rectification product. Thus, during one step of operation the air flows through the path adjacent that of the recycle gas and during the next step it flows through the path remote from that of the recycle gas. In a regenerative reversing exchanger, the principal cause of temperature fluctuations is more obvious since during one step of operation a cold stream of rectification product flows therethrough to chill its mass and during the next step a warm stream of air flows therethrough to recover the stored refrigeration; from the start to the end of each step of the operation it is clear that the temperature of the regenerator changes and these temperature changes are naturally reflected in the temperatures of the gaseous streams issuing therefrom.

It is an object of this invention to provide a process of producing oxygen in which such temperature fluctuations are materially reduced, desirably to the point where variations in the temperature of a gas stream entering the expander or rectification system or reversing exchanger is of the order of 1° F.

Another object is to provide a novel arrangement of apparatus for practicing such process.

Other objects and advantages of this invention will be apparent from the following detailed description thereof.

In accordance with this invention a gas stream of the oxygen process which tends to fluctuate in temperature, after leaving the reversing exchanger and before entering into a succeeding stage of the process, such as the expander, rectification system, or before being recycled through the reversing exchanger, is passed through a chamber containing a predetermined mass of high heat conducting material presenting a large heat transfer surface area and so designed that little pressure drop takes place in the gas stream passing therethrough. Such chamber functions as a damper to check or limit temperature fluctuations and is herein referred to as a damper chamber. Once the steady state of operation is reached this damper chamber functions to bring the gas stream exiting therefrom to the desired temperature at which the gas should enter the succeeding stage of the process. Accordingly, if the gas stream entering this chamber is above this desired temperature, the gas stream gives up its excess heat to the chamber and leaves at a temperature substantially the same as or a little above the desired temperature, e. g., about 1° F. above this temperature. On the other hand, if the entering gas is at a temperature below this desired temperature, it is heated in its flow through this chamber and leaves at a temperature close to the desired temperature. The damper chamber in operation is accordingly heated or cooled as the entering gas stream flowing therethrough enters at a temperature above or below the desired temperature, the gas stream leaving this chamber at a temperature little above or below the desired temperature. Desirably the chamber contains a weight of high heat conducting material, preferably metal, over which the gas stream passes, of from 1% to 10% by weight of that in the flow path of the reversing exchanger with which it is associated, preferably about 5% of the weight of heat conducting material in such a flow path.

In the accompanying drawings forming a part of this specification and showing for purposes of exemplification preferred layouts of equipment for practicing the process of this invention,

Figure 1 illustrates diagrammatically a preferred layout of apparatus for practicing the process of this invention, which apparatus involves reversing exchangers in which the air and rectification products flow in indirect heat exchange relation, i. e., reversing exchangers of the recuperative type;

Figure 2 illustrates a modified arrangement of apparatus for practicing the process of this invention in which the reversing exchangers are of the regenerative type; and

Figure 3 is a section through one form of damper chamber taken in a plane normal to the line of flow of gas therethrough.

It will be understood the drawings illustrate diagrammatically preferred apparatus for practicing this invention, but the invention may be carried out in other apparatus, for example, any desired number of reversing exchangers may be used in lieu of those shown in the drawings; each of the reversing exchangers may be replaced by two or more smaller exchangers placed in series and/or parallel, if desired, and other rectification systems may be used in lieu of that shown in the drawings.

Referring to Figure 1, 10 is a heat exchanger which may be of any well known type and which in the drawing is shown consisting of two sections 11 and 12. In the embodiment shown in

the drawing, section 11 consists of a single shell in which are provided two flow paths, namely, interior path 13 and concentric path 14, disposed in heat exchange relation with each other. Section 12 consists of three paths 15, 16 and 17 disposed in concentric relationship in heat exchange relation with each other. Each section has in each of the paths suitable fins of heat conducting material, e. g., copper or aluminum, promoting rapid and efficient heat exchange between gaseous media flowing through the paths in heat exchange relation with each other. For purposes of illustration and in the interests of simplicity, each flow path in an exchanger is shown on the drawings as consisting of a single tube, the several paths being disposed concentrically. Actually, however, each path in each exchanger may comprise a multiplicity of tubes for flow therethrough. As the construction of the heat exchanger per se does not form a part of this invention, and as it may be of any well known type, it is believed further description thereof is unnecessary.

Paths 13 and 14 of exchanger section 11 are connected with paths 16 and 17 of exchanger section 12 by lines 18 and 19, respectively. Section 12 also contains flow path 15 for flow of a minor portion of the cold air stream therethrough. This flow path leads into a line 20 which communicates with a damper chamber 21. This chamber contains a predetermined mass of high heat conducting material, such as copper or aluminum, presenting a large heat transfer surface area and designed so that little pressure drop takes place in the gas stream passing therethrough. For example, damper chamber 21 comprises a housing 22 (Figure 3) having therein a plurality of longitudinally extending channels 23 produced by winding on a suitable support 24, a strip of aluminum having one side 25 flat and the other side 26 provided with closely spaced integral ribs 27 to produce a plurality of convolutions having the closely spaced ribs extending across the width of each convolution and forming the longitudinally extending channels 23 in the annular spaces between the convolutions, the ribs of one convolution contacting the flat surface of a contiguous convolution. Such strip may have an overall thickness of approximately .07 inch and the ribs may be spaced apart a distance of approximately .15 inch from the center of one rib to the center of the next rib. Thus an exceptionally large mass of high heat conducting metal and high area of surface is provided per unit of volume of damper chamber. The type of packing hereinabove described is disclosed more fully and claimed in co-pending application Serial No. 19,952, filed April 9, 1948, now Patent No. 2,602,645. Alternatively, the damper chamber 21 may be constructed and designed so that it is similar to the regenerators disclosed and claimed in co-pending application Serial No. 783,498, filed November 1, 1947, now Patent No. 2,585,912, or may be of any other suitable construction providing a mass of high heat conducting material presenting a large heat transfer surface area and so designed that little pressure drop takes place in the gas stream passing therethrough.

Paths 13, 16 and 14, 17 of regenerator sections 11 and 12 are the paths through which air and nitrogen flow, the flow of these two media through their respective paths being periodically reversed so that during one step of the process air flows through paths 14, 17 and nitrogen

through paths 16, 13 and upon reversal during the succeeding step air flows through paths 13, 16 and nitrogen through paths 17 and 14. Reversal of flow is accomplished by suitably positioning reversing valves 29, 30 which may be of any well known type. Valve 29 is disposed in a pipe line system consisting of an air inlet pipe 31, nitrogen exit pipe 32 leading to any suitable point of nitrogen disposal and pipe lines 33, 34 leading to one end of paths 13, 14. Lines 35, 36 lead from paths 16, 17, respectively, to valve 30. Air exit line 37 leads from valve 30 and nitrogen inlet line 38 leads into this valve.

A second heat exchanger 39 is provided consisting of two sections 40, 41, which exchanger in general is similar to heat exchanger 10, except that it is approximately one-fourth the volumetric capacity of heat exchanger 10. Section 40 is provided with concentric flow paths 42, 43 and section 41 with the concentric flow paths 44, 45 and 46. Paths 42 and 45 are connected by a line 47 and paths 43 and 46 by a line 48. Oxygen and air periodically flow through paths 42, 43 of section 40 and paths 45, 46 of section 41 in heat exchange relation with each other and with a stream of nitrogen flowing through path 44 of section 41. The flow of air and oxygen through their respective paths is periodically reversed so that during one step of the process air flows through paths 43 and 46 and oxygen flows through paths 45 and 42. Upon reversal during the succeeding step, air flows through paths 42 and 45 and oxygen through paths 46 and 43. Reversal of flow is accomplished by suitably positioning the reversing valves 49 and 50 which may be of the same type as valves 29 and 30. Valve 49 communicates with the main air line through line 51 and is connected by lines 52 and 53 to one end of paths 42, 43. Valve 49 is provided with an oxygen exit line 54 leading to a suitable oxygen storage tank or point of consumption. Valve 50 is connected to the cold end of paths 45, 46 by lines 55, 56, respectively. Air line 57 leads from valve 50 into a line 58 into which also leads the air line 37 from valve 30. Oxygen line 59 leads into valve 50. Line 58 leads into a damper chamber 60 which may be of the same general construction as damper chamber 21, except that it is of substantially larger capacity to accommodate the flow of air passing therethrough.

A line 61 leads from damper 60 into an air line 81 and a line 62 provided with a control valve 63. A branch line 64 leads from line 62 and is equipped with a control valve 65. A minor portion of the air flowing into line 62 flows through branch line 64 into the flow path 15 of exchanger section 12 in heat exchange relation with the air and nitrogen flowing through the other two flow paths 16 and 17 in this exchanger section.

A line 67 leads from flow path 44 through a damper chamber 66 which may be of the same general type as damper chambers 21 and 60 hereinabove described. A minor portion of nitrogen passed through flow path 44 flows through line 67 and damper chamber 66 into nitrogen line 38 which in turn leads into valve 30. It will be understood that, if desired, the minor nitrogen stream may be passed through flow path 15 in exchanger section 12 in heat exchange relation with the air and nitrogen streams flowing through the other two flow paths in this exchanger and the minor air stream passed through flow path 44 in exchanger section 41 in heat exchange rela-

tion with the air and oxygen passing through the other two flow paths in this exchanger.

Reversing exchangers 10 and 39 may be placed in vertical, horizontal, or any other desired position. When these exchangers are arranged vertically, the colder end may be above or below the warmer end. While two exchangers have been shown, it will be understood that any desired number may be employed. In general, the nitrogen flow paths through the exchangers should have approximately four times the volumetric capacity of the oxygen flow paths. If desired, exchangers in which the oxygen and nitrogen flow paths are of the same volumetric capacity may be employed, in which case four air-nitrogen reversing exchangers are employed for each air-oxygen reversing exchanger. Also, of the total air cooled by indirect heat exchange with the oxygen and nitrogen products of rectification, about 20% flows through the air-oxygen reversing exchanger and about 80% through the air-nitrogen exchanger.

A line 70 leads from the damper chamber 21 into an expander 71 which may be a centrifugal expander or turbine of any well known type. Line 62 communicates with this line 70. By control of valve 65 a portion of the air which is to be expanded, say about 35%, flows from line 62 into and through line 64, path 15 where the air is warmed, imparting some of its cold content to the air flowing in a countercurrent direction through exchanger section 12. The thus warmed air leaves path 15 through line 28, passes through damper chamber 21 and flows through line 10. By control of valve 63 in line 62, the remaining portion of the air to be expanded, say about 65%, flows from line 62 into line 70 where it mixes with the warmed air flowing through this line, the resulting air mixture thus being warmed to a temperature such that no condensation or formation of liquid air takes place in expander 71 with consequent improvement in the efficiency of the expander. The expanded air leaves expander 71 through a line 72 leading into the low pressure stage of a rectification system hereinafter described.

The rectification system 75 comprises two columns 76 and 77. Column 76 is operated at a pressure of from about 60 to about 100 pounds, preferably at about 70 to 85 pounds and column 77 at a pressure of from about 2 pounds to about 12 pounds, preferably at about 5 pounds. These columns, as customary, are provided with rectification plates of the bubble-cap or other desired type. Air is supplied to the base portion of the high pressure column 76 through a line 78 which passes through a non-reversing heat exchanger 79 and leads from a second non-reversing heat exchanger 80. The air line 81 leads from air line 61 to this non-reversing heat exchanger 80. Crude oxygen containing approximately 40% oxygen, the rest being chiefly nitrogen, flows from the base of column 76 through line 82 which passes through a non-reversing heat exchanger 83. Upon flow through the expansion valve 84 in line 82 the crude oxygen is flashed entering column 77 at 85. A line 86 leads from the top of column 76, passes through a non-reversing heat exchanger 87 into a line having one branch 88 for returning liquid reflux comprising chiefly nitrogen to column 76 and another branch 89 passing through a non-reversing exchanger 90 and leading into the low pressure column 77 at 91. An expansion valve 92 is disposed in branch 89.

As hereinabove described, expanded air from expander 71 enters the low pressure column 77 through line 72. The base of this column is provided with a line 93 passing through the non-reversing heat exchanger 87, this line having a return portion 94 leading into the low pressure column 77 at 95. The lines 93 and 86 and the cooperating heat exchanger 87 function as a condenser-reboiler; liquid oxygen flows through line 93 through exchanger 87 in indirect heat exchange relation with the gaseous stream comprising chiefly nitrogen passing through line 86 which causes vaporization of the liquid oxygen to take place, the oxygen vapors flowing into column 77 at 95. Nitrogen line 96 leads from the top of column 77 to exchanger 90. A line 97 leads from exchanger 90 to exchanger 83. A line 98 leads from exchanger 83 to exchanger 79. A line 99 leads from exchanger 79 and is provided with branch 100 leading into flow path 44 of exchanger section 41. Flow through branch 100 is controlled by valve 101. Branch line 38, flow through which is controlled by valve 102, leads from line 99 to reversing valve 30.

A valve controlled drain line 103 communicates with line 93 through which the body of liquid oxygen in the base of tower 77 may be drained, when desired.

In operation of the equipment of Figure 1, air from the main air line at a pressure of 60 to 100 pounds and a temperature of 70° to 110° F. is divided into two streams, one of which flows through line 31, valve 29, line 34, flow path 14, line 19, flow path 17, leaving through line 36 and flowing through valve 30, line 37 into line 58. The air stream is thus cooled in its flow through flow paths 14 and 17 to a temperature near its liquefaction point and all carbon dioxide and moisture, if any, removed therefrom and deposited in the flow paths 17 and 14 of exchanger sections 12 and 11, respectively.

Nitrogen flows from the low pressure column 77 through line 96, into exchanger 90, line 97, exchanger 83, line 98, exchanger 79, line 99. From this line a minor portion of this nitrogen stream, say about 10% by volume, flows through branch line 100, into and through flow path 44 in exchanger section 41. The nitrogen is thus warmed by heat exchange with the air stream flowing through exchanger section 41. The thus warmed nitrogen stream exits through line 67 and flows through the damper chamber 66, which minimizes fluctuations in the temperature of this nitrogen stream. The nitrogen from chamber 66 flows at a substantially constant desired temperature into branch line 38 where it mixes with the major portion of the nitrogen flowing through this branch line. The mixture at a substantially constant temperature, since the major portion of the nitrogen is at a substantially constant temperature, enters valve 30 and flows from this valve through line 35, flow path 16, line 18, flow path 13, line 33 and valve 29, exiting through the nitrogen exit line 32.

Another air stream flows from the main air line through line 51, valve 49, line 53 into and through flow path 43, line 48, into and through flow path 46, line 56, valve 50, line 51 into line 58 where it joins the air stream from line 37. Simultaneously, oxygen from the low pressure column 77 flows through line 59, exchanger 30 into valve 50, line 55, flow path 45 where the oxygen flows in heat exchange relation with the air and nitrogen flowing through paths 46 and 44, respectively. The oxygen from flow path 45 flows through line 75 ess.

41, flow path 42 in exchanger section 40, through line 52, valve 49 and thence into the oxygen exit line 54. The air is thus cooled to a temperature close to its liquefaction point in its flow through flow path 46. This thus cooled air from line 58 flows as a unidirectional stream through damper chamber 60 over the large mass of high heat absorbing material therein, thereby minimizing temperature fluctuations and causing the cooled air to enter lines 81 and 62 through line 61 at a substantially constant temperature.

A minor portion of the air stream in line 62, e.g., about 20%, flows partly through line 64 into and through flow path 15 where it is warmed by heat exchange with the countercurrent air stream flowing through flow path 17. This warm air stream flows through line 20 and damper chamber 21 which functions to minimize fluctuations in the temperature of the air stream entering line 70. The other part of the minor portion of the air stream from line 62 flows into line 70 where it mixes with the warm air flowing therethrough, the mixture entering expander 71 at a substantially constant temperature such that substantially no liquid air is formed in the expander 71. The expanded air from expander 71 flows through line 72 and enters the low pressure stage 77 of the rectification system 75.

The remaining major portion of air, e.g., about 80% of the air from line 61, flows through line 81 into the non-reversing exchanger 80 where the air is further cooled by the oxygen flowing in indirect heat exchange relation therewith through line 59. From exchanger 80 the air flows through exchanger 79 where it is still further cooled by flowing in indirect heat exchange relation with the nitrogen passing through this exchanger, the thus cooled air entering the high pressure column 76.

Upon reversal, as indicated by the dotted setting of reversing valves 28, 30, 49 and 50, which reversal may take place every three minutes, air flows through line 31, valve 29, line 33, flow path 13, line 19, flow path 16, line 35, valve 30, line 37 into line 58. Air also flows through line 51, valve 49, line 52, flow path 42, line 47, flow path 45, line 55, valve 50, line 51 into line 58 where it mixes with the air stream flowing into this line 53 from line 37. The air in its flow through the exchangers 10 and 39 is cooled to a temperature close to its liquefaction point, this temperature, however, fluctuating depending upon the variables affecting the operation of the exchanger.

Simultaneously, a minor portion of the nitrogen flowing through line 99 passes through branch line 100 into and through flow path 44, line 67, damper chamber 66, into the nitrogen line 38 where it mixes with the nitrogen flowing through this line. The resultant mixed nitrogen stream passes through valve 30, line 36, flow path 17, line 19, flow path 14, line 34, valve 29 into the nitrogen exit line 32. The product oxygen stream flows through line 59, valve 50, line 56, flow path 45, line 48, flow path 43, line 53, valve 49, exiting through oxygen line 54. The flow of the various streams into and from the expander, into, through and from the rectification system, are the same as hereinabove described.

It will be noted that flow through the flow paths 44 and 15 of exchanger sections 41 and 12, respectively, always takes place in the same direction throughout the operation of the process. Flow of the nitrogen and air through their

respective flow paths in exchanger 10 and the flow of the oxygen and air through their respective flow paths in exchanger 39 is periodically reversed. Flow of the gaseous streams through damper chambers 21, 69 and 66 always takes place in a unidirectional path over the mass of high heat conducting material therein, the temperature of the gas stream entering this path fluctuating within relatively wide limits, say 10° F. or even more, and the gas stream exiting with materially smaller temperature fluctuations, say only 1° or 2° F. Reduction in temperature fluctuations of the gas streams entering the expander, rectification system and reversing exchangers improves the operation of these units. For example, by having the nitrogen enter the flow path in section 12 at a controlled substantially constant temperature, it is possible to have the nitrogen enter at a temperature close to that of the exiting air stream so that throughout the operation there is a relatively small temperature differential between the temperature of the exiting air stream and of the entering nitrogen stream thereby improving the purging effected by the nitrogen stream.

One example of the operation of the process of this invention in the apparatus shown in Figure 1 is described below. It will be understood this example is given for purposes of exemplification only and the invention is not limited thereto. The example refers to an oxygen plant operating in a locality where the atmospheric pressure is 13.1 pounds per square inch absolute.

Air under pressure of 74.6 pounds and a temperature of 95° F. is supplied through lines 31 and 51 to valves 29 and 49, respectively. The air flows through the flow paths in the exchangers 10 and 39 and leaves these flow paths at a temperature fluctuating within the range of -270° to -280° F.; the air then flows through damper chamber 60 leaving this chamber at a temperature of about -275° F., at which temperature it enters lines 81 and 62.

Approximately 20% of the total air introduced into the process is expanded in expander 71. Of this air to be expanded, approximately 33% flows through line 64 into flow path 15, entering this path at a temperature of -275° F. and being heated in its flow through this path to a temperature within the range of from -195° to -205° F. The air stream then flows through damper chamber 21, exiting from this damper chamber at a temperature of about -200° F. The remaining 67% of the air to be expanded at a temperature of -275° F. passes through line 62, mixing with the air stream flowing through line 70, producing a mixed air stream having a temperature of about -250° F., and a pressure of 72.9 pounds. This mixed air stream enters expander 71 and is expanded to a pressure of 6.4 pounds, its temperature being reduced to about -305° F., at which temperature and pressure it is introduced into low pressure column 77.

The remainder of the total air, approximately 80%, at a temperature of -275° F. flows through line 81 into heat exchanger 80 where it passes in heat exchange relation with an oxygen stream at a temperature of -293° F., flowing through line 59 from the low pressure column 77. The air is thus cooled to a temperature of -276.5° and the oxygen stream warmed to a temperature of -283° F., at which temperature it enters one or the other of the flow paths 45, 46 in exchanger section 41. The air at a temperature of 75

-276.5° F. passes through the heat exchanger 79 in heat exchange relation with the nitrogen stream flowing into this exchanger at a temperature of -293° F. and undergoes partial liquefaction (about 1.5% being liquefied) and passes at a temperature of -276.5° F. and a pressure of 72 pounds into the high pressure column 76. The nitrogen flowing through heat exchanger 79 is thus warmed to a temperature of -290.4° F.

About 8.5% by volume of the nitrogen stream at a temperature of -290.4° F. flows through line 100 and flow path 44, leaving this flow path at a temperature of from -195° to -205° F., at 15 which temperature it flows through line 67 and damper chamber 66, leaving this damper chamber at a temperature of about -200° F., at which temperature it mixes with the remaining major portion of the nitrogen stream flowing through line 38. The resulting nitrogen stream has a temperature of about -283° F., at which temperature it enters exchanger section 12. The nitrogen leaves exchanger section 11 at a temperature of 82.7° F. and under substantially atmospheric pressure.

Oxygen at a temperature of -293° F. and a pressure of 6.6 pounds flows through heat exchanger 80 where, as above described, its temperature is elevated to -283° F., at which temperature it enters exchanger section 41, and leaves exchanger section 40 at a temperature of 82.7° F. and at substantially atmospheric pressure.

In the operation of the rectification system 75, 35 crude oxygen at a temperature of -280° F. and a pressure of 72 pounds passes through line 82, and heat exchanger 83, in indirect heat exchange relation with nitrogen flowing into this exchanger. The crude oxygen is thus cooled to 40 a temperature of -287.6° F. and is then flashed in its flow through expansion valve 84, entering column 77 as a vapor-liquid mixture at a temperature of -302.5° F. and a pressure of 6.2 pounds. Nitrogen at a temperature of -316.5° F. and a pressure of 5.4 pounds flows through line 96 into heat exchanger 90 where it is warmed to a temperature of -303° F. in indirect heat exchange with the nitrogen reflux stream flowing through branch line 89. The nitrogen at a 50 temperature of -303° F. flows through exchanger 83 where it is warmed to a temperature of -293° F., at which temperature, as hereinabove described, it enters exchanger 79.

Oxygen at a temperature of -293° F. and a pressure of 6.6 pounds flows through line 93, is warmed in its flow through exchanger 87 to a 55 temperature of -287° F. by indirect heat exchange with a nitrogen stream flowing through line 86. The oxygen flows through line 94 into the base of column 77. From exchanger 87 a portion of the nitrogen flows through line 88 to the top of column 76, the remainder of the nitrogen flowing through branch line 89 and through exchanger 90 where it is cooled to a temperature 60 of -301.2° F. The nitrogen at this temperature is flashed in its flow through valve 92; its temperature is thereby reduced to -316.5° F. and its pressure to 5.4 pounds, at which temperature and pressure it enters the top of column 77.

Upon reversal which may take place every three minutes, the air passes through the paths in exchangers 10 and 39 through which the nitrogen and oxygen passed during the preceding step of the process and the nitrogen and oxygen pass through the paths in exchangers 10 and 39

11

through which the air passed during the preceding step of the process. The flow of the various streams is otherwise substantially the same as hereinabove described and the temperature and pressure conditions remain the same. The nitrogen in its flow through exchanger 10 and the oxygen in its flow through exchanger 39 remove by sublimation and evaporation the carbon dioxide and frost, if any, deposited in the paths traversed by the air during the preceding step of the process. Thus, in the continual operation, upon each reversal the nitrogen and oxygen rectification products effect removal of the carbon dioxide and frost, if any, deposited in the paths through which the air has passed in the preceding step of the process.

The modification of Figure 2 differs from that of Figure 1 chiefly in that the reversing exchangers of Figure 2 are of the regenerative type, not the recuperative type, as in Figure 1, and the oxygen is recycled through the cold end of the regenerators to obtain temperature conditions therein facilitating purging. The rectification system of Figure 2 is substantially the same as that of Figure 1 and like parts are indicated by the same reference characters.

In Figure 2, a regenerator assembly is shown involving two regenerator pairs 105 and 106. Regenerator pair 105 consists of regenerators 107, 108, which may be and preferably are of the type disclosed and claimed in co-pending application Serial No. 783,498, filed November 1, 1947, now Patent No. 2,585,912, although any other suitable type of regenerator may be used, if desired. As shown in Figure 2, the upper regenerator 107 comprises a housing 109 having a top port 110, base port 111 and having a plurality of packing units 112 therein. Each packing unit desirably consists of a tubular support 113 on which is mounted a stack 114 of thin plate-like polygonal members of high heat conducting material, desirably aluminum or copper, each having in the face thereof a multiplicity of closely spaced passages formed by cutting the plate-like members along closely spaced lines and deflecting the material between each such pair of lines to provide vanes defining these passages. One end of the tubular support 113 leads into a header 115 and the other end into a second header 116. For a more complete description of the construction of such packing units reference may be had to the aforesaid co-pending application.

Regenerator 108 structurally is substantially the same as 107. Regenerator pair 106 consists of regenerators 117 and 118, each structurally substantially the same as regenerator 107. Regenerators 107 and 108 and 117 and 118 have the ports 110 and 111 interconnected for flow from one regenerator to another, as shown in Figure 2.

Header 116 of regenerator 107 is connected with header 115 of regenerator 108 by a main 119. A main 120 connects header 116 of regenerator 117 with header 115 of regenerator 118. The two mains 119 and 120 are connected by a main 121.

The top headers 115 of regenerators 107 and 117 are connected by a main 122. The bottom headers 116 of regenerators 108 and 118 are interconnected by a main 123. In the apparatus of Figure 2, streams of nitrogen rectification product and air flow alternately over the packing units disposed within the regenerator pairs 105, 106, the nitrogen imparting its cold content to the packing members and the air recovering this cold when it flows thereover during the succeeding step of the process. Oxygen rectification

75

12

product flows through main 122, headers 115, tubes 113, giving up its cold content to the packing members, which cold content is recovered by the air passing over the packing members. The oxygen leaves regenerators 108, 118 through main 123.

A portion of the oxygen flowing through mains 119, 120 is withdrawn through lines 121, 124 by blower 125 and is passed through a damper chamber 126 of the same type as damper chamber 21 of Figure 1, which minimizes fluctuations in the temperature of the oxygen stream thus withdrawn. This oxygen stream from damper chamber 126 passes through a line 127 leading into a non-reversing exchanger 128 through which passes a minor portion of the air stream flowing through a line 129 into expander 71. The minor portion of the air stream is thus heated to a predetermined constant temperature at which temperature it enters expander 71. From exchanger 128 the warmed oxygen stream flows through a line 130 into an exchanger 131 through which flows the nitrogen stream passing through line 132, the nitrogen stream thus being warmed by the oxygen stream flowing through exchanger 131. From exchanger 131 the oxygen stream enters oxygen line 59 where it mixes with the oxygen stream flowing from the low pressure column 11, the resultant mixed oxygen stream entering main 122 communicating with the top headers 115 in the regenerators 107 and 117.

As above indicated, the recirculated oxygen passing through exchanger 128 warms the minor portion of the air stream flowing through line 129 to a temperature such that when introduced into the expander 71 liquefaction of air within this expander does not take place. From the expander 71 the expanded air is supplied to the low pressure stage 77 of the rectification system through line 72. In exchanger 131 the recirculated oxygen flows in indirect heat exchange relation with the nitrogen which flows from the rectification system through line 132. Thus the nitrogen enters the regenerator pair 105 or 106 at a higher temperature than would otherwise be the case. This nitrogen flows through one of the regenerator pairs 105, 106 and removes therefrom carbon dioxide and other condensibles deposited therein by air during the preceding step of the process. The efficiency of the purging action of the nitrogen is materially improved by its entering the regenerator pairs 105, 106 at such higher temperature as hereinabove described, since the preheating of the nitrogen in this manner results in temperature conditions within the regenerator optimum for the removal of the carbon dioxide.

Reversal of flow of nitrogen and air through regenerator pairs 105, 106 is accomplished by a pair of reversing valves 133, 134. Reversing valve 133 is provided with an air inlet 135, a pair of lines 136, 137 leading to ports 111 of the regenerators 108, 118 and a nitrogen exit line 138. The other reversing valve 134 is provided with a pair of lines 139, 140 leading to the ports 110 of regenerators 107, 117, nitrogen line 132 and an air exit line 141. This air exit line communicates with the damper chamber 142 corresponding to damper chamber 60 of Figure 1 and of the same construction. From damper chamber 142 a line 81 leads to non-reversing exchanger 80, as in the modification of Figure 1. Air line 81 is provided with the branch line 129 through which, as hereinabove described, a minor portion of the cooled air flows from line 81 through exchanger 128 to expander 71.

In the operation of the apparatus of Figure 2, air at a pressure of 60 to 100 pounds and a temperature of from 70° to 110° F. is supplied through line 135 and, as indicated by the full line valve settings, flows through valve 133, line 137 into and through regenerators 118, 117 where it is cooled to a temperature close to its liquefaction point at the pressure prevailing in these regenerators. The thus cooled air exits through line 140 into valve 134 from which the air flows through line 141 and damper chamber 142. A major portion of the air leaving this chamber at a substantially constant temperature flows through line 81 into the non-reversing exchanger 80, and thence through line 78 and exchanger 79 into the rectification column 76. The remaining minor portion of the cooled air flows through line 129, heat exchanger 128 to expander 71. From this expander the expanded air at a pressure of from 2 to 12 pounds passes to the low pressure stage 71 of the rectification system. Simultaneously, nitrogen flows through line 132, valve 134, line 139, regenerators 107, 108 giving up its cold to the packing units in these regenerators. The thus warmed nitrogen exits through line 136, valve 133 and nitrogen exit line 138.

Oxygen from the rectification system flows through line 59, exchanger 80, main 122, headers 115, tubes 113 within the regenerators 107, 117, headers 116 and connecting mains 119, 120. A portion of this oxygen is withdrawn as product through main 123 after its flow through the headers and tubes in the regenerators 108, 118. The remainder is recirculated by blower 125 through damper chamber 126, which minimizes fluctuations in the temperature of the oxygen stream that is recirculated. From damper chamber 126 the oxygen stream passes into exchanger 128 where it serves to warm the minor air stream flowing to the expander 71. From this non-reversing exchanger 128 the recirculating oxygen stream flows through line 130 into non-reversing exchanger 131 where it serves to warm the nitrogen stream flowing through line 132. From this non-reversing exchanger 131 the recirculated oxygen stream enters line 59 at a temperature substantially the same as the temperature of the oxygen flowing through this line, the resultant oxygen stream being passed through the headers 115, 116 and connecting tubes 113 in the regenerator pairs 105, 106, a part of the oxygen being withdrawn through main 121 and line 124 by pump 125 and the rest withdrawn as product from main 123, as hereinabove described.

Upon reversal, which may take place every three minutes, as indicated by the dotted line valve settings, air flows through valve 133, line 139, regenerators 108, 107 and is refrigerated close to its liquefaction point in its flow through these regenerators. The air exits through line 130 and flows through valve 134 into line 141, and thence through the same flow paths, as hereinabove described. Simultaneously, nitrogen flows through line 132, valve 134, line 140, regenerators 117, 118, exiting through line 131, valve 133 and nitrogen exit line 138. Oxygen flows through the same paths as during the preceding step of the process, namely, through the tubes in the regenerator pairs 105, 106 concurrently with the stream of nitrogen flowing through regenerators 117, 118 and countercurrent to the stream of air flowing through the regenerators 107, 108 in indirect heat exchange relation therewith. The nitrogen which alternately flows through one or the other of the

regenerator pairs 105, 106 removes therefrom carbon dioxide and other condensibles deposited therein from the air during the preceding step of the process.

It will be noted the process of this invention minimizes fluctuations in the temperature of a gas stream leaving the reversing exchanger and entering the expander or rectification system, or being recycled through the reversing exchanger. Hence, it effects a material improvement in the efficiency of the process, in that it permits the operation of the expander, the rectification system and the reversing exchangers under optimum conditions.

It is preferred to effect removal of moisture and carbon dioxide both in the reversing exchangers. It will be understood, however, that, if desired, the moisture may be removed from the air by any conventional means and dry air containing carbon dioxide passed through the exchangers, as hereinabove disclosed. In the event dry air is supplied to the equipment of Figure 1, reversing valves 29, 49 may advantageously be moved to a position between exchanger sections 11, 12 and 40, 41 so that the reversal of the air and nitrogen streams and of the air and oxygen streams occurs only in sections 12 and 41, wherein the carbon dioxide is deposited by the air stream. Operation of such equipment is preferably carried out so that the temperature at the warm end of exchanger sections 12 and 41 is at least slightly higher than the temperature at which carbon dioxide begins to deposit from the air streams. In general, the warm end of these exchangers should be at a temperature above about -180° F.

The expressions "reversing the flow of air and nitrogen" and "reversal" are used herein in the sense commonly employed in this art, namely, to mean the switching of the flow of two streams, for example, the air and the nitrogen or oxygen streams, so that upon each "reversal" the air flows through the path through which had previously flowed the nitrogen or oxygen and the nitrogen or oxygen flows through the path through which had previously flowed the air.

Since certain changes may be made in carrying out the above processes without departing from the scope of the invention, it is intended that all matter contained in the above description shall be interpreted as illustrative and not in a limiting sense.

What is claimed is:

1. An improvement in the process of producing oxygen by the liquefaction and rectification of air involving flow of air under pressure through a reversing exchanger in indirect heat exchange relation with a rectification product, periodically reversing the flow of air and rectification product through their respective paths of flow in said reversing exchanger, passing a portion of the thus cooled air through at least the cold end of said reversing exchanger to warm said air and produce temperature conditions within said reversing exchanger to facilitate purging thereof by the rectification product passing therethrough, and expanding the warmed air to produce refrigeration in amount adequate to compensate for enthalpy loss and heat leaks into the system, which improvement comprises passing the warmed air flowing from said reversing exchanger through a unidirectional path of flow containing a substantially isothermal mass of high heat conducting material to mini-

imize fluctuations in the temperature of said warmed air prior to expanding same.

2. An improvement in the process of producing oxygen by the liquefaction and rectification of air in low and high pressure stages involving flowing air under pressure through a reversing exchanger to recover the cold content of a rectification product, dividing the air into two streams, one consisting of a minor portion of the air and the other a major portion, expanding the minor stream thereby supplying to the process refrigeration in amount adequate to compensate for enthalpy loss and for heat leaks into the system, introducing the expanded air into the low pressure stage of the rectification system, introducing the major portion of the stream of air into the high pressure stage of the rectification system, rectifying the air to produce said rectification product, passing the rectification product through said reversing exchanger to impart its cold content to the incoming air stream, and periodically reversing the flow of air and rectification product through their respective paths in said reversing exchanger, the improvement which comprises passing said minor portion of the air stream through a unidirectional path of flow over a substantially isothermal mass of high heat conducting material prior to expanding same to minimize fluctuations in the temperature of the air stream subjected to expansion.

3. The process of producing oxygen by the liquefaction and rectification of air in low and high pressure stages involving flowing air under pressure through a reversing exchanger to recover the cold content of a rectification product, passing the air stream leaving said reversing exchanger through a unidirectional path of flow over a substantially isothermal mass of high heat conducting material to minimize fluctuations in the temperature of said air stream, dividing the resulting air stream into minor and major portions, dividing the minor portion into two parts, passing one of said parts in indirect heat exchange relation with the air and rectification product to warm said part of the air stream, thereafter passing the thus warmed part of the air stream in a unidirectional path of flow over a substantially isothermal mass of high heat conducting material to minimize fluctuations in the temperature of this air stream, mixing the resulting air stream with the second part of the minor portion to produce a mixed air stream at a temperature such that on expansion no liquefied air is formed in the expander, expanding the resulting air stream, introducing the expanded air into the low pressure stage of the rectification system, introducing the major portion of the stream of air into the high pressure stage of the rectification system, rectifying the air to produce said rectification product, passing the rectification product through said reversing exchanger to impart its cold content to the incoming air stream, and periodically reversing the flow of air and rectification product through their respective paths in said reversing exchanger.

4. A process of producing oxygen which comprises flowing two streams of air through paths in a pair of heat exchange zones, in one of said zones flowing a stream of nitrogen rectification product in indirect heat exchange relation with one of said air streams and in the other of said zones flowing a stream of oxygen rectification product in indirect heat exchange relation with the other of said air streams, periodically reversing the flow of air and oxygen and of air

and nitrogen through their respective paths in said zones, mixing the air streams leaving both of said zones into a common stream, passing the thus mixed air stream through a unidirectional path of flow over a substantially isothermal mass of high heat conducting material to minimize fluctuations in the temperature of the resulting air stream, introducing the resulting air stream at a substantially constant temperature into the rectification system, rectifying the air to produce said oxygen and nitrogen products of rectification, and passing the said oxygen and nitrogen rectification products through their flow paths in the said zones.

5. A process of producing oxygen which comprises flowing two streams of air through paths in a first and second heat exchange zone, in the first zone flowing a stream of nitrogen rectification product in indirect heat exchange relation with one of said air streams and in the other of said zones flowing a stream of oxygen rectification product in indirect heat exchange relation with the other of said air streams, periodically reversing the flow of air and oxygen and of air and nitrogen through their respective paths in said zones, mixing the air streams leaving both of said zones into a common stream, passing the thus mixed air stream through a unidirectional path of flow over a substantially isothermal mass of high heat conducting material to minimize fluctuations in the temperature of the resulting air stream, dividing the air stream into major and minor portions, introducing the major portion of the air into a high pressure stage of a rectification system comprising high and low pressure stages, recirculating the minor portion of the air through the first-mentioned zone in indirect heat exchange relation with the air and nitrogen passing therethrough thus warming the recirculated air stream, passing the warmed air stream in a unidirectional path of flow over a substantially isothermal mass of high heat conducting material to minimize fluctuations in the temperature of the warmed air stream, expanding the resulting warmed air stream, introducing the expanded air into the low pressure stage of the rectification system, rectifying the air to produce said oxygen and nitrogen products of rectification, and passing the said oxygen and nitrogen rectification products through their paths in the said zones.

6. A process of producing oxygen by the liquefaction and rectification of air, which comprises flowing air under pressure through a heat exchange zone through which also flows a rectification product to recover the cold content of said rectification product, recirculating through said heat exchange zone a second rectification product in indirect heat exchange relation with the air and the first-mentioned rectification product passing therethrough thus warming the second-mentioned rectification product, passing the thus warmed second rectification product through a unidirectional path containing a substantially isothermal mass of high heat conducting material to minimize fluctuations in the temperature of said second stream of rectification product, passing the said second stream of rectification product in indirect heat exchange relation with the first-mentioned rectification product flowing to said heat exchange zone to warm said first-mentioned rectification product, and periodically reversing the flow of air and

the first-mentioned rectification product through said heat exchange zone.

7. A process as defined in claim 6, in which the first-mentioned rectification product is nitrogen, the second-mentioned rectification product is oxygen, and the air stream leaving said heat exchange zone is passed in a unidirectional path over a substantially isothermal mass of high heat conducting material prior to introduction into a rectification system to minimize fluctuations in the temperature of the air stream entering said rectification system.

8. In an apparatus for the liquefaction and rectification of mixed gases involving: a heat exchanger having a first flow path and a second flow path in indirect heat exchange with each other to effect transfer of heat from a feed stream of said mixed gases to a stream of gaseous rectification product thereof flowing, respectively, through said first flow path and said second flow path; reversing means at each end of said heat exchanger for periodically flowing said feed stream through said second flow path and said rectification product stream through said first flow path; a third flow path in said heat exchanger in indirect heat exchange with at least one of said first and second flow paths to warm a gaseous stream derived from said feed stream after flowing through said heat exchanger, each of the aforesaid three flow paths containing a mass of high heat conducting material; the improvement which comprises a thermally isolated damper chamber containing a mass of high heat conducting material and having an inlet and an outlet, and a conduit connecting said inlet directly and solely to the discharge end of said third flow path.

9. Apparatus as defined in claim 8, in which the outlet of said chamber is connected to the inlet of an expander.

10. Apparatus as defined in claim 8, in which said chamber contains a mass of high heat conducting material of from 1% to 10% by weight of the weight of such material in the third flow

path in said heat exchanger, with which said chamber communicates.

11. In the liquefaction and rectification of air involving: flow of air under pressure through a first flow path wherein said air is cooled to a temperature near its liquefaction point to condense and deposit out carbon dioxide; flow of a cold rectification product of said air through a second flow path wherein said rectification product is warmed and sublimes a carbon dioxide deposit from said second flow path; periodic reversal of the flow of said air and said rectification product through said second flow path and said first flow path, respectively; and flow of a cold stream derived from said cooled air through a third flow path in indirect heat exchange with at least one of said first and second flow paths to warm said stream and to facilitate the sublimation of carbon dioxide; the improvement which comprises passing said stream, after flowing through said third flow path and while still substantially at the temperature at which said stream discharges from said third flow path, through a unidirectional flow path containing a substantially isothermal mass of high heat conducting material to minimize fluctuations in the temperature of said stream.

12. The process of claim 11 wherein said stream flowing through said third flow path is nitrogen rectification product.

13. The process of claim 11 wherein said stream, after passing through said unidirectional flow path, is expanded with the performance of work to provide refrigeration to said process.

JOHN A. HUFNAGEL.
